UNITED STATES PATENT OFFICE.

JOHN S. GREENE, OF ROCHESTER, NEW YORK, ASSIGNOR TO THE PHOTOSTAT CORPORATION, OF ROCHESTER, NEW YORK, A CORPORATION OF NEW YORK.

SHEET-HANDLING DEVICE.

Application filed May 25, 1926. Serial No. 111,659.

The present invention relates to photography, and more particularly to apparatus for conveying prints through a definite path, such as through successive baths for treatment. It is also in the nature of an improvement upon the apparatus disclosed and claimed in my prior Patent #1,421,079 issued June 27, 1922.

An object of the invention is to provide improved and simplified means for disengaging the prints or sheets from the conveying means, and for depositing them at a definite location, after the treatment has been completed; which will operate with certainty; which will insure quick and positive disengagement of a print from the conveyor with a minimum of mutilation of the print or sheet; which will be automatic in action; which will not require attention or supervision by the attendant or operator; and which will be relatively simple, dependable, durable and inexpensive.

Various other objects and advantages will appear from the following description of an embodiment of the invention, and the novel features will particularly be pointed out hereinafter in the appended claims.

In the accompanying drawings:

Fig. 1 is a side elevation of a portion of photographic apparatus of the commercial or copying type, to which has been attached print releasing means constructed in accordance with the invention, the print releasing means being shown in the poised or set position ready for operation;

Fig. 2 is a plan of the same;

Fig. 3 is a side elevation, on a different scale, of the print releasing means at about the instant when it becomes active to release a print;

Fig. 4 is an elevation similar to Fig. 3, but showing the relative positions of the parts just after the kicker member has disengaged a print from the impaling means;

Fig. 5 is a sectional elevation somewhat similar to Fig. 3, but showing in full parts otherwise more or less hidden in Fig. 3; and

Fig. 6 is an elevation, from another direction, of a portion of the print releasing mechanism.

In the illustrated embodiment of the invention, a pair of parallel endless flexible members 1 are connected together at one or

more intervals by cross bars 2 and the endless members with the bars constitute what may be referred to as a conveyor. The endless members 1 may be of any suitable construction, such as endless chains, and may be guided through a desired path of travel by suitable pulleys or sprockets 3 so that the endless members may move successively into and out of suitable chambers or tanks (not shown) as disclosed in my prior patent hereinabove referred to. After leaving the last tank however, the endless members are conducted in an approximately horizontal direction, as shown in Fig. 1, for example over a receptacle 4 into which the prints are to be deposited.

Each cross bar 2 is provided with one or more spears or pins 5 for piercing or impaling and carrying therewith a sheet or print 6. The spears or impaling pins 5 preferably extend from their bar in the direction of travel of that section of the conveyor formed by the endless members and the cross bars, in order that any drag on the prints will not pull them off over the ends of the pins upon which they are impaled.

In the particular illustrated example, the conveyor after passing over the receptacle 4 into which the prints are to be deposited passes over a sprocket wheel 3, and then passes in a return direction above and in spaced relation to the stretch of the conveyor which is over the receptacle 4.

A shaft 7 extends between and is rotatably supported by the opposite side walls of the apparatus preferably above the upper stretch of the conveyor. Arms 8 are fixed to the opposite end portions of the shaft 7, depend along the sides of the conveyor, and then toward one another into the space between the stretches of the conveyor. A U-shaped piece 9 is secured by one of its arms to the extreme free end of each arm 8. The other arms of the pieces 9 at opposite sides of the conveyor are connected together by a bar 10. The distance between the U-shaped pieces 9 is less than the distance between the endless members or chains 1, so that the bar 10 may pass through the plane of two corresponding and connected stretches of the endless members 1.

The arms 8, U-shaped pieces 9, and the connecting bar 10 together serve, and may hereinafter be mentioned as, a kicker or striker member or device. The U-shaped pieces 9,

are positioned with their open ends extending forwardly in the direction of their travel during a striking operation which will be in the direction of travel of the lower stretch 5 of the conveyor immediately above the receptacle 4, so as to clear each cross bar 2 by embracing it when the bar 10 passes through the conveyor between corresponding stretches of the endless members in order to engage or 10 strike the print carried by that particular bar 2 as shown in Fig. 4.

An arm or lever 11 is also fixed upon and depends from the shaft 7 at one side of the apparatus, and at its free end is pivoted by 15 a pin 12 to one end of a lever 13 which is in turn pivoted by a pin 14 to an intermediate section of a lever 15. The lever 15 is pivoted at one end by a pin 16 to a suitable bracket 17. A helical tension spring 18 is connected at 20 one end to the free end of the lever 15, and at its other end is anchored by a pin 19 to a suitable part of the apparatus, so as to urge or bias the lever 15 yielding into the position shown in Fig. 4, in which it and the 25 spring extend in the same general direction and are in substantial alignment with one another, that is, in a dead center position. The levers 11 and 13 which constitute a toggle connection between the lever 15 and the 30 shaft 7 of the kicker member, are of such length that they will be in a broken or acute position when the spring 18 and the lever 15 are substantially aligned as shown in Fig. 4.

Obviously then, when the toggle levers 11 35 and 13 are moved into a straight line or dead center position, as shown in Figs. 3 and 5, the spring 18 will be tensioned to a greater extent than that which it possesses in Fig. 4. When the toggle levers are moved past dead 40 center position and into the position shown in Fig. 1, the spring 18 will tend to continue the movement, but such movement will be limited by a pin 20 disposed in the path of one of the toggle levers, such as 11. This 45 limited position is shown in Fig. 1, and the arms 8 of the kicker member are so fixed upon the shaft 7, angularly with respect to the toggle lever 11, that the cross bar 10 of the kicker member will be poised or held above 50 the plane of the lower stretch of the endless conveyor section which is shown in Fig. 1, when the toggle lever is against the limit pin 20.

A shaft 21 is mounted in a suitable bracket 55 22 attached to the frame of the apparatus at one side thereof. An arm or trigger 23 is fixed to the shaft 21, and extends upwardly into the path of travel of the cross bars 2 in the lower stretch of the conveyor section shown 60 in Fig. 1, so that when a cross bar 2 strikes the trigger 23 it will oscillate and then release the shaft 21. A bell crank lever 24 is also fixed upon the shaft 21 for oscillation therewith, and one arm 25 of the bell crank engages 65 with a pin 26 which is carried by the toggle

lever 13. Hence when the trigger 23 is rocked by any bar 2 it will rock the bell crank 24, and the latter will shift the toggle levers from the position shown in Fig. 1 to and through the dead center position shown in Figs. 3 and 5, 70 whereupon the spring 18 will snap the toggle levers further in the same direction and carry the kicker member into embracing relation with the particular cross bar 2 which actuated the trigger. 75

The striking movement of the kicker member will be from the rear and in the direction of travel of that conveyor section so as to strike any print thereon, drive it forwardly of its movement with the conveyor, and thus 80 push it off of the impaling pins. The print will thereupon drop into the receptacle 4. The other arm of the bell crank 24 carries a counter weight 27 which returns the trigger 23 and the shaft 21 to their normal positions 85 immediately upon their release. An abutment screw 28 may be threaded through the bracket 22 for engagement with the bell crank to limit its return movement, and thus by adjusting the screw 28 the initial position of 90 the bell crank may be varied to some extent.

The shaft 7 also has fixed thereto a reset arm 29 which depends within the path of the cross bars 2 after the latter have actuated the trigger 23 to release the kicker member. As a 95 matter of convenience, the arm 29 depends into the path of the cross bars 2 in the upper stretch of the section of the conveyor which is shown in Fig. 1. The engagement and operation of the reset arm 29 by a cross bar 2 causes 100 a movement of the shaft 7 in a direction to cause the movement of the kicker member out of the path of other of the cross bars 2 which are moving toward the paper release mechanism. The shaft 7 in moving the kicker member to its poised or reset position also shifts the toggle members through dead center position and into the position shown in Fig. 1, where they are held yielding against the stop or limit pin 20 by the spring 18. 110

In the operation of this apparatus, the endless members or chains 1 are driven in any desired manner, such as in prior patent referred to, and at a certain point in their travel the prints or sheets are engaged (such as by 115 the means of my prior patent referred to above) over the impaling points 5, so that the prints or sheets will be drawn through a definite path with the conveyor which path may include any number of developing, fix- 120 ing and washing baths for the prints.

After the prints have been carried through the desired course they approach the position shown in Fig. 1. When the cross bar 2 carrying a print engages with the trigger 23, the shaft 21 and the bell crank 24 will be rocked, and the latter acting upon the pin 26 will shift the toggle levers through dead center position, whereupon the spring 18 will snap the kicker member from the dead center position 125 130

shown in Fig. 3 into the position shown in Fig. 4 where the U-pieces embrace the cross bar. During such movement the bar 10 strikes the print 6 sharply, at a point adjacent to the cross bar, in a manner to drive the print or sheet forwardly and off of the impaling pins as shown in Fig. 4. The print thus released drops into the receptacle 4 or upon any platform provided at that point.

10 During continued movement of the conveyor, the cross bar 2 will engage with the reset arm 29 and reset the kicker member in the manner explained. The action is thus automatic, and the print or sheet is disengaged by 15 pushing it off the impaling means in such a manner that there is practically no mutilation of the print or sheet. The receptacle 4 may, if desired, contain a final fixing or washing liquid, as shown in Fig. 4, although it may 20 merely constitute a receiving basket.

It will be obvious that various changes in the various details, which have been herein described and illustrated in order to explain the the nature of the invention, may be made 25 by those skilled in the art within the principle and scope of the invention as expressed in the appended claims.

I claim as my invention:

1. In photographic apparatus, a conveyor 30 provided with means for catching and carrying a print, and a device supported independently of the conveyor and controlled thereby for striking the print in a manner to disengage it from the carrying means when the print reaches a desired point in its travel with the conveyor.

2. In photographic apparatus, a conveyor 40 provided with impaling means for engaging with and conveying a print, and means supported independently of the conveyor adjacent the path of travel of the print at the point where disengagement of the print is desired for impelling the print in a direction ahead of the impaling means for an instant to disengage it therefrom.

3. In photographic apparatus, a conveyor having means for engaging and moving a print, and means released by said print engaging means for striking the print at a 50 point in proximity to its point of engagement with the conveyor, in a manner to disengage the print from the conveyor.

4. In photographic apparatus, a conveyor having means for engaging and moving a print, and means released by said print engaging means for striking the print at a point in proximity to its point of engagement with the conveyor, in a manner to disengage the print from the conveyor, said conveyor being operative to reset the striking means automatically after a print has been disengaged.

5. In photographic apparatus, an endless conveyor having bars provided with impaling means for catching and carrying a print, and means released by said bar for striking

the print in a manner to disengage it from the impaling means when the print reaches a desired point in its travel with the conveyor.

6. In photographic apparatus, an endless conveyor having bars provided with impaling means for catching and carrying a print, means released by said bar for striking the print in a manner to disengage it from the impaling means when the print reaches a desired point in its travel with the conveyor, 70 and means engageable by said bar after said means has been released for striking a print, for resetting said striking means.

7. In photographic apparatus, endless conveying means for engaging and carrying a print, and means normally positioned between adjacent runs of said conveying means for striking a print and releasing it from said conveying means.

8. In photographic apparatus, means for 85 engaging and moving a sheet, and a device controlled by said engaging means and located adjacent the path of travel of the sheet with the said moving means for imparting a sharp movement to the sheet in a manner 90 to disengage it from said means.

9. In photographic apparatus, impaling means including a bar with an impaling projection extending therefrom and movable in a closed path for engaging and carrying 95 a sheet, and means within the path of movement of said bar operative automatically when the sheet reaches a desired point in its movement for striking the sheet in a manner to disengage it from the impaling projection. 100

10. In photographic apparatus means including an impaling projection moving in a definite path for engaging and carrying therewith a sheet, a kicker device including a member located adjacent the path of travel of 105 the sheet with the impaling means and operative when released to strike the sheet in a manner to disengage it from the impaling means, and means for resetting said kicker automatically after a release and operation. 110

11. In photographic apparatus, means movable in a definite path for engaging and carrying therewith a sheet and a device including a spring actuated kicker member located adjacent the path of travel of the sheet with 115 said means, normally held in an inactive position and in a position to be released by the travel of said means, for striking the sheet in a manner to disengage it from said means.

12. In photographic apparatus, means movable in a definite path for engaging and carrying therewith a sheet, a device including a spring actuated kicker member located adjacent the path of travel of the sheet with 125 said means, normally held in an inactive position and in a position to be released by the travel of said means, for striking the sheet in a manner to disengage it from said means, and means operable by said means for re-

setting said kicker member after each operation.

13. In photographic apparatus, means movable through a definite path for engaging and conveying a print, a device including a kicker member located adjacent said means and operable to strike a print and disengage it from said means when the print reaches a desired point in its travel, means including a spring and toggle levers for normally holding said kicker member in an inactive set position and operative, when said toggle levers are shifted past dead center, to strike the print, and means operative by said conveying means for engaging and pushing the toggle levers past dead center to release the kicker member when the print reaches the desired point for its disengagement and is within the path of movement of the kicker member.

14. In photographic apparatus, means movable through a definite path for engaging and conveying a print, a device including a kicker member located adjacent said means and operable to strike a print and disengage it from said means when the print reaches a desired point in its travel, means including a spring and toggle levers for normally holding said kicker member in an inactive set position and operative when said toggle levers are shifted past dead center, to strike the print, means operative by said conveying means for engaging and pushing the toggle levers past dead center to release the kicker member when the print reaches the desired point for its disengagement and is within the path of movement of the kicker member, and means operable by said conveying means for resetting the kicker member and toggle levers and tensioning said spring after each print releasing movement of the kicker member.

15. In photographic apparatus, means movable through a definite path for engaging and conveying therewith a print, a kicker member located adjacent the path of travel of the print and operable in a path to strike the print in a manner to disengage it from said means when the print reaches a desired point in its travel, means including a spring and toggle levers for actuating said kicker member when said toggle levers are pushed in one direction past dead center, and means including a lever engageable with the toggle levers to push them past dead center position and effect a release of the print, said last means having an arm in the path of and operable by said conveying means, whereby said print will be released automatically when it reaches a desired point in its travel.

16. In photographic apparatus, means movable through a definite path for engaging and conveying therewith a print, a kicker member located adjacent the path of travel of the print and operable in a path to strike

the print in a manner to disengage it from said means when the print reaches a desired point in its travel, means including a spring and toggle levers for actuating said kicker member when said toggle levers are pushed in one direction past dead center, means including a lever engageable with the toggle levers to push them past dead center position and effect a release of the print, said last means having an arm in the path of and operable by said conveying means, whereby said print will be released automatically when it reaches a desired point in its travel, and means connected to said toggle levers for resetting them by a movement in a direction reverse to said one direction, and including a member disposed in the path of travel of said conveying means for a resetting operation thereby after the kicker member has been released.

17. In photographic apparatus, a conveyor including a pair of endless flexible members movable through a definite path for engaging and conveying a print and bars extending between said members for connecting the same and for movement therewith, said bars having impaling means for engaging and conveying therewith a print, and an element disposed adjacent one face of the conveyor formed by said members and bar and movable through the plane of the corresponding stretches of said members which are connected by said bars, for engaging with and detaching the print from said impaling means.

18. In photographic apparatus, a conveyor including a pair of endless flexible members movable through a definite path for engaging and conveying a print and bars extending between said members for connecting the same and for movement therewith, said bars having impaling means for engaging and conveying therewith a print, an element disposed adjacent one face of the conveyor formed by said members and bar and movable through the plane of the corresponding stretches of said members which are connected by said bars, for engaging with and detaching the print from said impaling means, a spring device connected to said element for operating it in a direction to disengage the print, and means controlled by said conveyor for instigating the print engaging movement of said element.

19. In photographic apparatus, means for engaging and conveying a print through a definite path, a lever pivoted at one end, a helical tension spring connected at one end to the other end of the lever and anchored at its other end so as to urge said lever into a position in which it extends in the direction of length of said spring, a kicker member mounted for oscillation in a path to strike and disengage a print carried by said means, a pair of toggle levers connected between

said lever and said kicker member for moving said member through a path to strike a print as said lever moves to normal position in alignment with said spring, said toggle levers serving to lock the kicker member in set position with said lever and spring out of alignment with one another, whereby when said toggle levers are pushed past dead center position in one direction, the kicker member will be released and spring operated to strike and disengage a print, and means controlled by said conveying means for pushing the toggle levers past dead center position in a direction to cause a striking movement of said kicker member.

20. In photographic apparatus means for engaging and conveying a print through a definite path, a lever pivoted at one end, a helical tension spring connected at one end to the other end of the lever and anchored at its other end so as to urge said lever into a position in which it extends in the direction of length of said spring, a kicker member mounted for oscillation in a path to strike and disengage a print carried by said means, a pair of toggle levers connected between said lever and said kicker member for moving said member through a path to strike a print as said lever moves to normal position in alignment with said spring, said toggle levers serving to lock the kicker member in set position with said lever and spring out of alignment with one another, whereby when said toggle levers are pushed past dead center position in one direction, the kicker member will be released and spring operated to strike and disengage a print, and means engaged and operated by said conveying means for in turn pushing said toggle levers past dead center position in a direction to cause the release of said kicker member.

21. In photographic apparatus, means for engaging and conveying a print through a definite path, a lever pivoted at one end, a helical tension spring connected at one end to the other end of the lever and anchored at its other end so as to urge said lever into a position in which it extends in the direction of length of said spring, a kicker member mounted for oscillation in a path to strike and disengage a print carried by said means, a pair of toggle levers connected between said lever and said kicker member for moving said member through a path to strike a print as said lever moves to normal position in alignment with said spring, said toggle levers serving to lock the kicker member in set position with said lever and spring out of alignment with one another, whereby when said toggle levers are pushed past dead center position in one direction, the kicker member will be released and spring operated to strike and disengage a print, means engaged and operated by said conveying means for in turn pushing said toggle levers past dead center position

in a direction to cause the release of said kicker member, and means also engaged and operated by said conveying means for shifting said toggle levers in a direction to reset the kicker member for a new operation.

22. In photographic apparatus, a pair of endless members movable through parallel paths, bars connecting said members and provided with means for engaging and conveying a print, a kicker member mounted for oscillation across the plane of the corresponding stretches of the members which are connected by any bar when said bar is in a desired point in its travel, a pivoted lever, a helical coil spring connected at one end to a free end of said lever and anchored at its other end so as to urge the lever into a position in which it is substantially aligned therewith, toggle levers connected to said lever and to said kicker member and occupying a dead center position when said spring is tensioned and said kicker member is approximately in set position for movement across the plane of the members to strike a print carried by said bar, whereby when the toggle levers are in one position past dead center said spring will be tensioned and the kicker member set for operation, and when moved past dead center position the kicker member will be released for operation by said spring to strike a print and disengage it from said bar, and means controlled by the conveyor formed of said members and bars for pushing the toggle levers past dead center position in a manner to release the kicker member for a print striking operation.

23. In photographic apparatus, a pair of endless members movable through parallel paths, bars connecting said members and provided with means for engaging and conveying a print, a kicker member mounted for oscillation across the plane of the corresponding stretches of the members which are connected by any bar when said bar is in a desired point in its travel, a pivoted lever, a helical coil spring connected at one end to a free end of said lever and anchored at its other end so as to urge the lever into a position in which it is substantially aligned therewith, toggle levers connected to said lever and to said kicker member and occupying a dead center position when said spring is tensioned and said kicker member is approximately in set position for movement across the plane of the members to strike a print carried by said bar, whereby when the toggle levers are in one position past dead center said spring will be tensioned and the kicker member set for operation, and when moved past dead center position the kicker member will be released for operation by said spring to strike a print and disengage it from said bar, means controlled by the conveyor formed of said members and bars for pushing the toggle levers past dead center position in a manner to release the

kicker member for a print striking operation, and means controlled by said conveyor for resetting said kicker member automatically.

24. In photographic apparatus, a pair of endless members movable through parallel paths, bars connecting said members and provided with means for engaging and conveying a print, a kicker member mounted for oscillation across the plane of the corresponding stretches of the members which are connected by any bar when said bar is in a desired point in its travel, a pivoted lever, a helical coil spring connected at one end to a free end of said lever and anchored at its other end so as to urge the lever into a position in which it is substantially aligned therewith, toggle levers connected to said lever and to said kicker member and occupying a dead center position when said spring is tensioned and said kicker member is approximately in set position for movement across the plane of the members to strike a print carried by said bar, whereby when the toggle levers are in one position past dead center said spring will be tensioned and the kicker member set for operation, and when moved past dead center position the kicker member will be released for operation by said spring to strike a print and disengage it from said bar, and a lever device having one arm in the path of travel of said bar and its other arm in position for engagement with one of said toggle levers, whereby movement of said bar is transmitted to the toggle levers for releasing the kicker member automatically.

25. In photographic apparatus, a pair of endless members movable through parallel paths, bars connecting said members and provided with means for engaging and conveying a print, a kicker member mounted for oscillation across the plane of the corresponding stretches of the members which are connected by any bar when said bar is in a desired point in its travel, a pivoted lever, a helical coil spring connected at one end to a free end of said lever and anchored at its other end so as to urge the lever into a position in which it is substantially aligned therewith, toggle levers connected to said lever and

to said kicker member and occupying a dead center position when said spring is tensioned and said kicker member is approximately in set position for movement across the plane of the members to strike a print carried by said bar, whereby when the toggle levers are in one position past dead center said spring will be tensioned and the kicker member set for operation, and when moved past dead center position the kicker member will be released for operation by said spring to strike a print and disengage it from said bar, and a lever device having one arm in the path of travel of said bar and its other arm in position for engagement with one of said toggle levers, whereby movement of said bar is transmitted to the toggle levers for releasing the kicker member automatically, said kicker member having connected thereto an arm disposed in the path of travel of said bars whereby the continued movement of said bars will shift said kicker member into set position automatically.

26. In a photographic apparatus, the combination with means for conveying a print in a horizontal path above a desired point of deposit and doffing means for imparting a positive forward movement to said print to remove it from said conveying means and deposit it at said point, the movement of said doffing means being in the same direction but at a greater speed than that of the conveying means.

27. In a photographic apparatus, the combination with a bar having a path of travel horizontally above a desired point of deposit and provided with impaling projections extending forwardly therefrom for engaging and moving a sheet therewith over the said point and means located independently of said bar and actuated by contact therewith for stripping a sheet from the impaling projections with a movement in the direction in which the latter extend and in the direction of travel of the bar but moving with greater speed than the latter to disengage the sheet and deposit it in the receptacle.

JOHN S. GREENE.
